William Mc Bright and James Mc Bright
Setters Patent

The schedule referred to in this Yellow Patent and a copy of the same containing a description in the words of the said William Mc Bright and James Mc Bright themselves of their improvement on the saw gin for picking cotton

To all to whom these presents shall come. Be it known that we William Mc Bright and James Mc Bright of the town of Newburgh Fairfield district State of So Carolina have invented certain new and useful improvements in the cotton saw gin & that the following is a full & exact description of the construction & operation of the machine as improved by us. The general appearance & operation of the machine as improved by us, is not different from the old mode of constructing them but our improvements consist in affording great facilities in keeping them in order while in operation & in keeping them in repair & from an absolutely cost or trouble. We claim as our improvements first a movable head, second sliding ribs & third the center of the bushing the posts on which they turn. The head is hung to the post of the gin with two hinges & can always be moved so as to get out the saws & bolts them when cheated with very little labor & without any risk of injuring the saws. In the former mode of having a stationary head when the saws were cheated, the whole top of the gin head had to be removed & we suppose the saws were liable ^{to} injury & the operation of clearing the saws not attended with much more labor than by this mode. The sliding ribs are fastened in the way now used to fasten them on the gin head, upon two long cross pieces called flat beams which are inserted into long mortises on each side of the gin head & confined there by screws which may at any time when the sliding ribs are want at one place be taken out so as to permit the flat beams to be let down in the mortises which are graduated so as to give the proper distance & to keep the flat beams level. The distance which we have used as the proper one for each move of the flat beams has been 3 ft 6 inches. The flat beams can in this mode be removed 4 or 5 times & each move under the flat beams as a new set of flats by the old mode of having them stationary when they move down so as to let fall seed & trash tho' them they had to be all taken

taken out and laid by a mechanice, by our improvement the hand who attends to the gun can remove them & remedy the inconvenience of their turning over too much. The points by our improved mode are made of cast steel about four inches ^{long} & 5/8 of an inch square pointed at each end that when one point is worn the other may be used. They are held & indented on a piece of cast metal & confined with an iron clamp & screw tap. The centers are fixed in a cast metal ring which is fitted on the end of the brush cylinder & secured there with three wood screws there being a round hole in the middle of the ring to receive the centre which is fitted into it similar to the stopper of a decanter when worn it can be taken out and another inserted without altering the size of the brush. The three above described improvements we claim as our invention being calculated to make the cotton save gun much more durable & more easily kept in order at a much less expense.

James Mc Bright,
Letter Patent

The schedule referred to in this Letter Patent, and making part of the same, containing a description in the words of the said James Mc Bright, himself of his improvement in the Reversed Cotton Gin.

To all whence it may concern,

Be it known that I James Mc Bright of the town of Lincolntown District, of Springfield in the state of South Carolina have invented certain new and useful improvements in the "New Haw Gin" called "Mc Bright's Reversed Cotton Gin," which are described as follows, reference being had to the annexed drawings of the same making part of this specification. The frame of the reversed gin consists of two sills (marked A in the annexed drawings) 3 feet 6 inches long of scantling 6 inches by 4 placed on their edge with a mortise through the center of each to receive two, main posts marked B, four feet 3 inches long of scantling, 6 inches by 4, with a mortise one foot above the top of the sills to receive a nail the length of the frame of scantling 6 inches by 4 marked C, tenoned at the top to receive a cap marked D, of scantling 6 inches by three. The nail D is to be mortised to receive the nail or marks E. The posts to carry the bush are marked F, and let into the sills at one end two inches in rear of the main posts and a screw bolt at the other end. The posts are 3 feet 4 inches above the sills of scantling 4 by 4 inches. The plank at the ends of the bush marked G forms a lip around the bush, and for the following breast or rest on. The hopper board is composed of two pieces of 1/2 inch plank worked out to the segments of a circle the lower edge fitted on the sills the upper edge having a recess inserted into it about one inch apart. The narrow piece of the hopper board is let down on the wire until it comes within 3 inches of the other piece both being made fast. The comb is made of sheet iron or steel 3/4 inches broad with notches opposite the wires, fastened on a board and standing nearly perpendicular for working on an iron pin with a screw below to fast the comb to or from the roll. A funnel turning on hinges, of moveable board, to which the sills are fastened. A. said ^{to} bush. An regulating screen and bags of the bush.

A. The tray and board. B. hopper board. C. comb to set in the hopper board. C. State. D. comb. E. board, to which the comb is fastened. F. wire pins on which the rough hairs. G. screw to set the comb. H. driving pulley.

The frame, funnel, saw, brush & graining, are made in the usual manner.

The machine is driven by horse, steam or other power. The improvement which I have made and desire to secure by Letters Patent consists principally, in giving a direction to the rotation of the saws contrary to that of the common gin, that is the saws turn towards the feed board instead of from it.

The advantages derived from this and the other improvement are 1. A great portion of the motes false seed, sand and trash being thus discharged before the picked cotton reaches the current of air about the teeth. The picked cotton consequently passes cleaner from the gin, while on the other hand in the common gin a great portion of sand, motes, false seed, and trash having to pass directly through the current of air when the picked cotton is floating, mixes with it and in consequence thereof a part of the cotton either sinks down with the trash or the trash rises and passes with the cotton through the funnel.

2. The seed are discharged as soon as picked, while in the common gin the seed has to pass round to where the seed cotton is sent in, and, some seed is always covered that ought to be discharged, by which means the seed is apt to be discharged in an irregular manner.

3. The weight of a large roll of cotton lies directly on the saws which will cannot be broken by one feeding, or a sudden jerk of the edge wheel, while in the common gin the roll being more or less off the saws is raised up and falls forward causing it to become hollow and over feeding or a sudden jerk of the edge wheel breaks and often throws it out.

4. The picking gin thus has the hair being done on the descent of the roll a high hard substance passing its way to the saws cannot remain there nor injure the teeth, which in the common gin the hard substance separates from the roll and lodging, against the saws often destroying a number of the teeth and sometimes the saws altogether are destroyed.

5. The hopper or finger board on the common gin is fixed and stationary having a rack and comb behind it which by pressing against the roll when the gin is in motion tears off the seed freely and with great regularity, while in the common gin the feed board being moveable either lets the seed out with too much cotton on it or by retaining the seed too long the cotton is slowly given out thus occasioning a loss of cotton on a loss of time.

6. The sand, false

Patent No.: X9358

false seed, motor, much leaf, and other trash pass out with the sand, and no good cotton is lost in any way; while in the common gin much cotton is wasted and lost and comparatively imperfectly cleaned from the cures before stated, which causes are entirely removed by the improvements now made in the cotton gin.
